UNITED STATES PATENT OFFICE.

SAMUEL G. WELLMAN, OF BRADFORD, PENNSYLVANIA.

VENTILATING-SASH LOCK.

1,187,583.

Specification of Letters Patent. Patented June 20, 1916.

Application filed December 1, 1915. Serial No. 64,476.

To all whom it may concern:

Be it known that I, SAMUEL G. WELLMAN, a citizen of the United States, residing at Bradford, in the county of McKean and State of Pennsylvania, have invented certain new and useful Improvements in Ventilating-Sash Locks, of which the following is a specification, reference being had therein to the accompanying drawing.

This invention relates to certain new and useful improvements on sash locks and more particularly to the general construction of sash lock as shown in my Patents No. 751,586, dated February 9, 1904, and No. 959,981, dated May 31, 1910; the object being to improve the general construction and to provide novel means for mounting the dog within the housing.

Another object of my invention is to provide a sash lock in which the dog and key are connected together and mounted within the housing within a suitable guide-frame arranged therein, so that the parts can be quickly assembled and after having been assembled, can be held in their proper positions in respect to each other.

Other and further objects and advantages of the invention will be hereinafter set forth and the novel features thereof defined by the appended claims.

In the drawing, Figure 1, is a perspective of my improved construction of sash fastener showing the application of the same to a window frame, the sash being shown with a rack to engage the dog of the fastener; Fig. 2, is a section through the housing showing the manner of mounting the dog and key; and Fig. 3, is a perspective of the housing, guide frame, dog and key, in position to be assembled.

Like numerals of reference refer to like parts in the several figures of the drawings.

In the drawing, 1 indicates a window frame provided with the usual stile 2 forming a groove to receive the window sash 3 which is provided with a rack 4 constructed substantially the same as shown in my Patent No. 959,981, dated May 31, 1910, although it is, of course, understood that various forms of rack can be used in connection with my improved construction of sash fastener, as will be hereinafter fully described, without departing from the spirit of my invention.

My improved construction of sash lock, 55 comprises a substantially cylindrical casing 5 adapted to be embedded within a suitable opening formed in the frame 1; said casing having oppositely disposed guide-ways 6 in which is mounted a guide-frame 7 adapted 60 to receive a dog 8 to which is connected a key 9, said frame having a configuration conforming in shape to the configuration of the dog 8 and key 9 in cross section, the lower portion of the dog having a lug 11 65 adapted to fit within a coil spring 10 seated within the bottom of the casing and normally holding the key and dog in extended position, as shown in Figs. 1 and 2.

The guide-ways 6 form projections on the 70 periphery of the casing 5 so that when the casing is driven into the opening of the frame 1, the casing will be prevented from turning within the opening.

The side of the casing adjacent the stile 2 75 is flattened as shown at 12 and the edge of the casing is provided with lugs 13 adapted to extend through suitable openings formed in a face-plate 14 and be swaged so as to secure the face-plate to the casing as shown 80 in Fig. 1.

The face-plate is provided with a flanged end portion 15 embracing the inner face of the stile 2 having spaced guards 16 projecting outwardly therefrom between which the 85 head 9' of the key is adapted to work, said head having a flange 9² adapted to be engaged by a lock pin 17 slidably mounted in the lower guard 16.

The plate 14 is provided with a suitable 90 opening through which the dog 8 extends so as to bring the same into engagement with the rack 4 of the window sash when the sash is in position within the frame, so that the window frame will be locked in its 95 adjusted position by said dog. When it is desired to allow the sash to move freely within the frame, the key 9 is pressed inwardly until the head thereof is beyond the locking pin 17 and by pressing upwardly 100 on the pin 17, the head thereof will embrace the flange 9² of the head of the key so as to hold the dog out of the path of travel of the rack and the window sash can be raised and lowered in the ordinary manner. The 105 flange 15 of the plate 14 is cut away as shown at 18 to receive the key 9 and when the plate 14 is removed, the dog and key

can be withdrawn from the casing. The plate 14 is also provided with an extension 14' separated from the main portion of the plate by a groove in order to allow the same 5 to be broken off when desired; this extension being used when an exceptionally wide sash is employed within the frame and by the use of such extension, the plate can be positioned within the groove of the window 10 frame. When used in a narrow groove, the extension is removed so as to allow the plate to be forced into position, as shown in Fig. 1.

The plate 14 is preferably embedded within the bottom of the groove, of the stile of 15 the window frame and can be secured therein, in any desired manner, although I have found that by securing the casing firmly within the opening of the frame, the plate will be held in its proper position without 20 the use of other fastening means and I do not wish to limit myself to any particular means of fastening the same within the frame.

From the foregoing description, it will be 25 seen that I have provided a sash lock composed of a casing adapted to be embedded within a window frame, having a face-plate provided with a flange to embrace the stile of the frame; said plate having openings to 30 receive the dog and key so that the same can be readily operated to throw the dog out of the path of travel of the rack of the window sash. It will also be seen that an exceptionally simple and cheap construction is provided and one in which novel means is 35 employed for mounting the dog and key within the casing.

I claim:

1. A sash lock, comprising a casing, a 40 frame arranged within said casing, a dog slidably mounted within said frame, a plate arranged over said casing having openings to receive said dog, and a key carried by said dog extending outwardly therefrom.

45 2. A sash lock, comprising a casing having oppositely disposed guide-ways, a frame mounted in said guide-ways and held therein by friction, a dog slidably mounted in said frame having a projecting lug, a spring arranged within said casing embracing said lug, and a key carried by said dog and extending outwardly therefrom.

55 3. A sash lock, comprising a casing adapted to be embedded within the window frame, having lugs projecting therefrom, a plate provided with openings to receive said lugs, said plate having an opening, a spring-actuated dog slidably mounted within said casing extending outwardly through said opening, and a key carried by said dog.

60 4. A sash lock, comprising a casing having oppositely disposed projections adapted to be embedded within an opening formed in a window frame, a face plate arranged over

said casing having an opening, a frame arranged within said casing, a dog slidably mounted within said frame, a spring for normally holding said dog in extended position, and a key carried by said dog extending outwardly therefrom.

70 5. A sash lock, comprising a casing adapted to be embedded within a window frame, a frame secured within said casing, a flanged face-plate arranged over said casing, said plate having an opening in the body thereof and a flange cut away centrally, a dog slidably mounted within said frame extending outwardly through the opening of said face-plate, and a key carried by said dog working in the cut away portion of the 80 flange of the plate.

6. A sash lock, comprising a casing adapted to be embedded within a window frame having a frame secured therein, a spring arranged under said frame, a dog working 85 in said frame having a key carried thereby, a face-plate provided with an opening to receive said dog arranged over said casing, said face-plate having a flange provided with a central cut away portion, and a key 90 carried by said dog within said casing having a portion extending outwardly through the cut away portion of the flange.

7. In a sash lock, a casing having a frame secured therein, a spring arranged under 95 said frame, a dog slidably mounted in said frame having a lug projecting within said spring, a face-plate extending over said casing having an opening to receive said lug, said face-plate being provided with a flange 100 having a central cut away portion and provided with spaced guards, a key carried by said dog working in the cut away portion of said flange, said key having a head arranged between the guards of said flange. 105

8. In a sash lock, the combination with a window frame having a stile and provided with an opening in the body thereof adjacent said stile, of a casing provided with oppositely disposed projections secured 110 within said opening, a frame arranged within said casing, a spring arranged under said frame, a dog slidably mounted within said frame having a projection extending within said spring, a face-plate secured over 115 said casing provided with an opening to receive said dog, a flange formed on said face-plate embracing the stile of the window frame, said flange having a central cut-away portion and provided with spaced guards, 120 and a key carried by said dog working in the frame of said casing and having a portion extending out through the cut-away portion of said flange, said key terminating in a head arranged between the guards of 125 said flange.

9. A sash lock, comprising a casing having outwardly projecting lugs, a face-plate hav-

ing openings to receive said lugs, a frame arranged within said casing, a spring arranged under said frame, a dog slidably mounted in said frame extending outwardly 5 through the opening formed in said plate, and a key carried by said dog extending outwardly therefrom.

In testimony whereof I hereunto affix my signature in the presence of two witnesses.

SAMUEL G. WELLMAN.
